SPONGE APPLICATOR TOP FOR A SQUEEZE BOTTLE

Peter Chesney Carveth, Hamden, Conn., assignor to The International Silver Company, Meriden, Conn., a corporation of Connecticut

Filed May 16, 1966, Ser. No. 2,314

Term of patent 14 years

(Cl. D58—26)

FIG. 1 is a front elevational view of a sponge applicator top for a squeeze bottle, showing my new design; FIG. 2 is a side elevational view thereof, the opposite side being a mirror image of FIG. 2;

FIG. 3 is a rear perspective view thereof; and

FIG. 4 is a top plan view.

A squeeze bottle is shown in broken lines for illustrative purposes only.

I claim:

The ornamental design for a sponge applicator top for a squeeze bottle, as shown and described.
